Petroleum Iron Works Company of Ohio,
Petroleum, Ohio, a corporation of Ohio

Application March 26, 1941, Serial No. 99,917

Term of patent 14 years

To all whom it may concern:

Be it known that I, Edgar E. Shanor, a citizen of the United States, residing at Sharon, in the county of Mercer and State of Pennsylvania, have invented a new, original, and ornamental Design for a Turnbuckle Body, of which the following is a specification, reference being had to the accompanying drawing, forming part hereof, wherein—

body showing my new design.

I claim:

The ornamental design for a turnbuckle body,
as shown.

EDGAR E. SHANOR.
